DESIGN.

—o—
J. S. McMAHON.

VEGETABLE DISH.

No. 15,308.

Patented Aug. 19, 1884.

UNITED STATES PATENT OFFICE.

JOHN S. McMAHON, OF HAMILTON, ONTARIO, CANADA.

DESIGN FOR A VEGETABLE-DISH.

SPECIFICATION forming part of Design No. 15,308, dated August 19, 1884.

Application filed June 4, 1884. Term of patent 3½ years.

To all whom it may concern:

Be it known that I, JOHN S. McMAHON, residing at Hamilton, Province of Ontario, Canada, have invented and produced a new and original Design for a Vegetable-Dish, of which the following specification is a full, clear, and exact description, reference being had to the accompanying photographic illustration, forming part of this specification.

10. This invention relates to a new configuration for a vegetable-dish or other piece of breakfast or dinner ware.

15. In the photographic illustration, the letter A represents the dish, and B its cover. The dish A is of oblong form, and has four sides, a, their edges tapering from top to bottom. At the upper edge and along the corners of the dish extend ridges b, in imitation of bamboo. The upright ridges at the corners run 20 out into feet c, made in imitation of the root

of the bamboo. d is one of the handles. It is a ring in imitation of bamboo, and passes through two plain staples, e, with open shanks. The cover B has ridges g, in imitation of bamboo, at the edges of its sides, f. Two of these 25 ridges connect at the top of the cover, and are there turned upward to form a loop, i, through which the handle h extends.

I claim as my invention—

1. The design for a vegetable-dish, having 30 tapering edges, and ridges b terminating in feet c, in imitation of bamboo and its root, as described and shown.
2. The design for a vegetable-dish, having ring-shaped bamboo handle d and plain open 35 staples e, as described and shown.

J. S. McMAHON.
